UNITED STATES PATENT OFFICE.

WILLIAM H. GORDON AND PHILIP J. BOOST, OF DETROIT, MICHIGAN.

CHEESE-SAFE.

SPECIFICATION forming part of Letters Patent No. 274,119, dated March 20, 1883.

Application filed February 2, 1883. (No model.)

To all whom it may concern:

Be it known that we, WILLIAM H. GORDON and PHILIP J. BOOST, of Detroit, county of Wayne, State of Michigan, have invented a new and useful Improvement in Cheese-Safes; and we declare the following to be a full, clear, and exact description of the same, such as will enable others skilled in the art to which it pertains to make and use it, reference being had to the accompanying drawings, which form a part of this specification.

Our invention consists in the combination of devices and appliances hereinafter specified, and more particularly pointed out in the claims.

15 In the drawings, Figure 1 is a side elevation of the device embodying our invention, showing parts in section. Fig. 2 is a front view. Fig. 3 is a variation. Fig. 4 is a vertical section. Fig. 5 is a plan view of a variation.

20 The object of our invention is, first, to provide an improved cheese-safe with a revolving cheese-board, which may be drawn forward from the interior of the safe, and which may be revolved when thus drawn forward as well as when in position within the safe; second, to provide a combined cheese-safe and refrigerator; third, to provide a cheese-safe adapted to keep the atmosphere suitably moist, and thus prevent the cheese from drying up; fourth, 25 to provide a cheese-safe with a door adapted to slide back over the top or to be rolled up upon a roller or be opened outward upon hinges, with a revolving cheese-board adapted to be drawn forward from the interior of the safe, the construction being such that by opening the door said cheese-board shall be simultaneously drawn forward, or when the cheese-board is drawn forward the door will be raised simultaneously, and vice versa; fifth, to pro-

30 vide a cheese-safe in which the glass may be shipped without danger of breakage and be readily secured in place when wanted for use or sale; sixth, to provide a cheese-safe of such dimensions as to leave little or no waste room, 35 and in consequence of which its construction may be materially cheapened.

In carrying out our invention, A represents the corner-posts of the safe. A' is the top. A² is the bottom.

40 B is a cheese-board, pivoted in the center to

the sliding board B', constructed to be drawn forward from the interior of the safe, so that the cheese-board B may be wholly removed from the interior of the safe. We prefer to provide suitable rollers, b, located beneath the 55 sliding board, to facilitate its removal, and also rollers b' beneath the revolving board.

We are aware that a cheese-board has been constructed adapted to revolve within the interior of the safe and to be drawn forward, in 60 which case, however, the position of the pivot remains unchanged, and the cheese-board, when drawn forward, cannot be revolved. It is evident that in our device, however, since the cheese-board is pivoted to the sliding board 65 B', the location of the cheese-board upon its pivot remains unchanged whatever may be its position, whether within or without the safe, and it may therefore be revolved when drawn forward, thus greatly facilitating the cutting 70 of the cheese; and since it may thus be drawn out from the interior of the safe when the cheese is to be cut, the height of the safe can be limited, as it is unnecessary to have much space above the cheese, as is required where 75 the cheese must be cut without removing it from the interior.

C represents vessels of any suitable shape or size, secured in any proper manner within the safe, adapted to contain ice or water, by 80 means of which the temperature may be maintained at a desired point and the air within the safe prevented from becoming dry, thereby absorbing the moisture of the cheese.

D is a shelf suspended in the interior of the 85 safe. This may or may not be used in cheesesafes of our invention.

E is a door, preferably a flexible door, adapted to slide back over the upper part of the safe, as shown in Fig. 1, in which case 90 said door is made of rigid material; or said door may be constructed of canvas and rolled upon a suitable roller, e, as shown in Fig. 2, located at the top of the safe; or a door may be hinged at one side and open outwardly, as 95 shown in Fig. 5.

e' is a cord connecting the door with the sliding board B, said cords passing over suitable pulleys, e², or other suitable gear. In case the door is constructed to slide up and backward 100

- or to roll up, this cord is attached to the top of the door and to the rear of the sliding board. In case, however, the door opens outwardly, the cord is attached to the bottom of the door and to the front of the sliding board; or the board may be secured directly to the door, in which case the board is constructed of a suitable form and pivoted at e^3 , as shown in Fig. 5.
- 10 e^3 is a cord secured to the lower edge of the door, passing over a pulley, e^4 , and connected with the sliding door at the rear. It is evident by means of the attachment of these cords, whenever the sliding board is drawn forward, the door will also be lifted, or when the door is lifted the sliding board will be brought forward. In case the door is hinged at the side, whenever the door is opened, the sliding board will also be drawn outward.
- 15 20 F represents panes of glass. We prefer to secure these panes in place by means of rabbeted moldings F', one of said moldings being secured in place by one or more screws, the construction being such that by removing the molding upon one side the pane may be slipped into its proper position and secured therein by fastening said molding in place by means of the screw. The glass may be stored for shipment in any convenient manner—as, for
- 25 30 instance, the bottom of the safe may be provided with a molding, a, within which, and beneath the bottom A², the glass may be packed for shipment.
- When the safe is desired for use or sale, the 35 glass can be readily adjusted into its place with very little difficulty, as already described.
- Instead of the rabbeted molding F', the corner-posts A, or the top and bottom of the safe, may be constructed with an interior rabbeted 40 edge, and the panes of glass may be secured therein by means of suitable buttons. We would have it understood that we contemplate securing the glass in place by either of these means.
- 45 50 It is evident also that, instead of panes of glass, wire-cloth may be substituted without departing from the principle of our invention.
- It is evident in case a door is used which slides upward and backward, or is rolled up, as before described, it will facilitate the closing of the door if it is suitably weighted at the bottom. In use of such doors, also, it would be convenient if the sliding board B' be constructed to project forward, so that the door, 55 when closed, may rest upon its outer edge. When so constructed it can be reached and drawn forward without the necessity of first raising the door. The door may also be provided with any suitable catch to hold it in position when closed. We design also to have the cord connecting the door and sliding board so secured in place that it may be at any time detached from said sliding board whenever it 60 may be desired.
- 65 5 What we claim is—

1. The combination, with a cheese-safe constructed with a stationary bottom, of a sliding board provided with a rotary cheese-board, the construction being such that the cheese-board may be rotated either within the safe 70 or when drawn forward, substantially as described.

2. A cheese-safe provided with a sliding board, carrying a rotary cheese-board, and a vessel or vessels located at the side or sides 75 of the safe above the cheese-board for containing a refrigerating material to keep the cheese moist, substantially as described.

3. In a cheese-safe, the combination, with a removable cheese-board, of a door connected 80 therewith, the construction being such that when the cheese-board is drawn forward the door will be opened, and vice versa, substantially as described.

4. In a cheese-safe, a removable rotary 85 cheese-board adapted to be revolved either within the safe or when drawn forward, substantially as described.

5. The method of securing glass in cheese-safes, consisting of three stationary rabbeted 90 moldings and a removable molding adapted to be secured in place by one or more screws, substantially as described.

6. In a cheese-safe, a flexible door weighted at the bottom and adapted to be rolled up, in 95 combination with a removable rotary cheese-board, the construction being such that when the sliding board is drawn forward the door will be raised, and when the cheese-board is inserted it will close by its own gravity, substantially as described.

7. The combination, with a cheese-board provided with a raised base, adapted to receive panes of glass for shipment, of fixed rabbeted 100 moldings adapted to receive three sides of a pane of glass, and a removable molding whereby the glass may be secured in position by means of a screw, substantially as described.

8. In a cheese-safe, the combination, with a sliding base provided with a revolving cheese-board adapted to be rotated within and without the safe, of a door connected with said sliding base by one or more cords, and in connection therewith pulleys over which said cords may operate, the construction being such that when 115 the sliding base is drawn forward the door will be opened, substantially as described.

9. In a cheese-safe provided with a stationary bottom, a sliding base, a cheese-board pivoted to said sliding base, and in connection 120 therewith suitable rollers located beneath said base, substantially as described.

In testimony whereof we sign this specification in the presence of two witnesses.

WILLIAM H. GORDON,
PHILIP J. BOOST.
